FOREIGN PATENT DOCUMENTS

(57) **CLAIM**

The ornamental design for a personal floatation device, as shown and described.

DESCRIPTION

FIG. 1 is a perspective view of a personal floatation device showing my new design;
 FIG. 2 is a front view thereof;
 FIG. 3 is a rear view thereof;
 FIG. 4 is a left view thereof;
 FIG. 5 is a right view thereof;
 FIG. 6 is a top view thereof;
 FIG. 7 is a bottom view thereof; and,
 FIG. 8 is a perspective view thereof shown in a use configuration with environment.
 The broken lines shown in the figures represent portions of the personal floatation device that form no part of the claimed design. The broken lines in FIG. 8 depict environment of a child that forms no part of the claimed design.
